(57) **CLAIM**

The ornamental design for an acoustic building element, as shown and described.

DESCRIPTION

FIG. 1 is a perspective view of a first embodiment of an acoustic building element showing my new design; FIG. 2 is a front view of the acoustic building element of FIG. 1, the side view from the left side being a mirror image thereof;

FIG. 3 is an end view of the acoustic building element of FIG. 1 taken from the right side, the rear view being identical thereto;

FIG. 4 is a perspective view of a second embodiment of an acoustic building element showing my new design;

FIG. 5 is a front view of the acoustic building element of FIG. 4, the side view from the left side being a mirror image thereof;

FIG. 6 is an end view of the acoustic building element of FIG. 4 taken from the right side, the rear view being identical thereto;

FIG. 7 is a perspective view of a third embodiment of an acoustic building element showing my new design;

FIG. 8 is a front view of the acoustic building element of FIG. 7, the side view from the left side being a mirror image thereof;

FIG. 9 is an end view of the acoustic building element of FIG. 4 taken from the right side, the rear view being identical thereto; and,

FIG. 10 is a top view of the first embodiment of an acoustic building element shown in FIG. 1 the top views of the second embodiment shown in FIG. 4 and the third embodiment shown in FIG. 7 being identical thereto.

No drawing figures showing a bottom view are provided, as the bottoms of the acoustic building elements are flat and include no surface ornamentation.

1 Claim, 10 Drawing Sheets
